(57) **CLAIM**

The ornamental design for a television stand, as shown and described.

DESCRIPTION

FIG. 1 is a right side perspective view of a television stand showing my new design;

FIG. 2 is a rear-right side perspective view thereof;

FIG. 3 is a front-left side perspective view thereof;

FIG. 4 is a second front-left side perspective view thereof;

FIG. 5 is a front-right side perspective view thereof;

FIG. 6 is a rear side perspective view thereof;

FIG. 7 is a second front-right side perspective view thereof;

FIG. 8 is a top perspective view thereof; and,

FIG. 9 is a top-right side perspective view thereof.

The television set is shown in broken lines for illustrative purposes only and forms no part of the claimed design.
